MAGNETIC DEFLECTING SYSTEM FOR
BEAUN TUBES

Ernst Ruska, Berlin-Zehlendorf, Germany, assignor to the firm of Fernseh Aktiengesellschaft, Zehlendorf, near Berlin, Germany

Application May 20, 1936, Serial No. 80,886
In Germany May 23, 1935

7 Claims. (Cl. 250—157)

The present invention relates to all types of cathode ray tubes in which the electron beam is deflected in two directions by means of magnetic fields, and relates more particularly to arrangements in which two magnetic fields disposed perpendicularly with respect to each other are produced at the same or nearly the same point on the axis of the deflected electron beam.

Cathode ray tubes generally possess a source of an electron beam of defined cross-section and a screen against which the electron beam is directed. A deflecting system is associated with such tubes to deflect the beam across the screen and produce a deflection pattern. Such deflecting systems usually consist of a pair of coils for each direction of deflection. The coils are placed around the tube and alternating currents pass therethrough to produce magnetic fields of varying intensity to deflect the electron beam. The fields produced by the deflecting systems hitherto used are not very homogeneous and therefore cause considerable distortion of the deflection pattern on the screen of the tube.

It is, therefore, an object of the present invention to provide a new and improved deflecting system. It is a further object of the present invention to provide a deflecting system which produces a substantially homogeneous magnetic field throughout the entire cross-sectional area through which the electron beam is deflected. A further object of the present invention is to provide a deflecting system composed of two individual systems in which each system produces linear deflection at a constant sensitivity of deflection independently of the other system. A still further object of the present invention is to provide a deflecting system in which substantially the entire cross-section of the magnetic field is limited to the cross-sectional area described by the electron beam when deflected by means of the present system so as to obtain a high degree of sensitivity as well as small inductivity in the system. In accordance with the present invention a system including two long coils is provided, whereby a homogeneous field is produced inside each long coil independently of its cross-sectional shape. According to the invention, the homogeneity of such fields is utilized for deflection purposes by causing the ray to enter and leave the field inside such a coil through the side walls thereof, and in a direction perpendicular to the axis of said coil. The coils may, in such case, be of circular or rectangular cross section, square, or, if desired, having regard to securing greater sensitivity and

at the same time lowest inductivity, they may have a trapezoidal cross section, so that the ray enters at the shorter of the two parallel sides of the trapezoid and emerges at the larger. For this purpose, naturally, the ray passage openings must be left free by suitably crimping the coils during winding.

The system according to the invention may be disposed outside, or in a particularly advantageous manner inside an evacuated electron ray tube. The advantage of the system resides in its great sensitivity (low control current consumption) accompanied by the greatest possible freedom from inductivity (reduced control distortion) as well as the great homogeneity of the control field (exact, constant system-sensitivity over the entire deflectional area).

The figures of the drawing illustrate constructional embodiments of the subject matter of the invention.

Fig. 1 is an arrangement used hitherto showing two coaxial deflection coils.

Fig. 2 shows the field path in a long deflecting coil having a homogeneous field.

Fig. 3 depicts an embodiment of a deflecting coil system in accordance with the invention.

Figs. 4 and 5 show a cross section and plan view respectively of a further embodiment of a coil system.

From the picture of the magnetic field shown in Fig. 1, it is evident that in the usual arrangements the field in the deflection space between the coils is non-homogeneous. On the other hand the field inside the coil as shown in Fig. 2 is absolutely homogeneous. Such a field, present inside a coil, is used for cathode ray deflection purposes in accordance with the present invention.

In Fig. 3 two coils 1 and 2 are provided which intersect each other at right angles. The axes of the coils lie in a plane perpendicular to the axis of the electron beam. The cross section of the coils in this case is chosen as trapezoidal. The cross sectional shapes of both coils are similar to each other and the coils intersect each other in such a manner that their longitudinal axes intersect the axis of the electron beam at the same point. The axial extent of both coils may be greater than the greatest extent of the coil cross section.

In the embodiment of Figs. 4 and 5, the entire double coil system has the shape of a square truncated section of a pyramid wherein each two opposite sides of the pyramid pertain to one coil winding. The size of the hollow space of the

pyramid in that case is somewhat greater than the cross-sectional area which the electron beam traverses during the deflection in order to render harmless the decreased homogeneity which 5 occurs in this embodiment owing to the short length of the individual coil, relative to its cross-section. The coil 3 is disposed on a framework 4 made of heat resisting material, e. g. ceramic material or glass. The frame 4 preferably contains 10 two plates 5, which are square, or else shaped corresponding to the dimensions of the deflection pattern produced by the electron beam. These plates receive and retain the coil windings wherefore their edges are provided with saw-tooth 15 shaped serrations. The plate through which the electron beam enters into the deflecting system is provided with a small hollow cylinder 6, whereas on the plate through which the beam emerges from the deflecting system is provided with a 20 raised retaining frame 7 which is formed as a continuation of the frame 4 and which surrounds the cross-section from which the beam emerges. The frame 7 may have a square shape or a shape according to the deflection pattern of the electron 25 beam. The convolutions are coiled sidewise around the raised edges of the members 6 and 7. The edges serve preferably also to attach the deflecting system to a supporting means (not shown). After the coil 3 is wound, rectangular, thin, insu- 30 lating disks 8 having a correspondingly bored-out, circular or rectangular hole are applied, which serve as a support for the second coil 9 and to insulate it from the first coil 3. Individual wires as well as groups of windings may be laid in the 35 tooth spaces 10 of the saw-toothed plates 5. This permits the adjustment of the specific field strength (ampere turns per centimeter of length of the individual coil), whereby the field strength along the axis of the coils can be controlled. The 40 entire deflecting system can be incorporated within the tube envelope 11, only a portion of which is shown in Fig. 4 of the drawing. Member 6 faces the source of the electron beam, while the member 7 faces the screen against which the 45 beam is directed.

The coils consist of turns of copper wire, preferably provided with an oxide or carbonate coating for insulation purposes, this coating being adapted to withstand the heating temperature 50 of the tube in case the deflecting system is operated inside the tube in a vacuum. Such coatings can be produced, for example, by means of a glowing furnace or an open flame and a regulated supply of air or oxygen, or by the admission of 55 carbon dioxide. The wire may however also be insulated by applying to its surface a coating of waterglass mixed with insulating particles, e. g. chalk.

The magnetic lines of force traversing the 60 inside of the coils are also present on the outside of the coils and form complete loops surrounding the coils. The electron beam will also be influenced by the fields on the inside of the coils. This influence should be prevented since these 65 edge fields are non-homogeneous. They cause a deconcentration of the electron beam on the outer portions of the deflection pattern produced by the system. The cross-section of the concentrated electron beam then assumes the aspect of two 70 small wedges standing tip to tip on each other. In order to render the outer fields as harmless as possible in their action, the magnetic flux on the outside of the coils should be guided by means of a ferromagnetic material into the same

plane, perpendicular to the axis of the electron beam, as the main flux, i. e. sidewise around the system. The components of the magnetic flux outside the coils intersecting the electron beam in front and back of the deflecting system, should 5 be weakened as much as possible. For this purpose the embodiment of Fig. 4 uses a closed ferromagnetic hysteresis-free and loss-less jacket (not shown) which likewise has the shape of a truncated pyramid section with or without bored- 10 out bottom and top plates and which is disposed over the windings so that the wires of the windings lie close thereto. The use of granulated low-loss materials is also feasible because of the high frequency of the deflection. Such a jacket aids 15 in producing a strongly homogeneous field inside each pyramidal coil and reduces the inductivity to the minimum possible value corresponding to the required beam deflection and beam intensity and at the same time increases the sensitivity to the 20 maximum value. In case longer individual coils are used, as shown in Fig. 3, the jacket likewise surrounds the entire system.

I claim:

1. In a cathode ray tube, a ray deflecting system 25 comprising two axially intersecting symmetrically cross-sectioned and congruent coils disposed normal each to the other, said coils having a trapezoidal cross-sectional form.

2. In combination with cathode ray deflecting 30 means after claim 1, means for insulating electrically said coils comprising a mixture of heat-resistant binding and non-conducting material.

3. In combination with cathode ray deflecting means after claim 1, means for insulating electrically said coils comprising a mixture of chalk 35 and water glass.

4. A cathode ray device comprising an envelope, a ray deflecting system including a coil form in said envelope and having an axial passage 40 therethrough for the ray, and windings wound on said form normal to each other, one of said windings enabling deflection of said ray in one direction, another of said windings enabling deflection of said ray in another direction. 45

5. A cathode ray device comprising an envelope, a ray deflecting system including a coil form of truncated shape having a small end and a large end, said coil form being disposed in said envelope with its smaller end facing the source of 50 said ray and having an axial passage therethrough sufficiently large at the larger end of said coil form to permit unobstructed deflection of said ray, windings wound on said form normal to each other, one of said windings enabling deflection of said ray in one direction, another of said windings enabling deflection of said ray in another direction. 55

6. A ray deflecting system for a cathode ray device comprising a coil form of truncated shape 60 having a small end and a large end and an axial passage therethrough, said passage being larger at the larger end of said form than at the smaller end, and a pair of windings wound on said form normal to each other. 65

7. A ray deflecting system for a cathode ray device comprising a coil form of truncated shape having a small end and a large end and an axial passage therethrough, said passage being larger at the large end of said form than at the small 70 end, a pair of windings wound on said form normal to each other, said form having a plurality of serrations to receive said windings.

ERNST RUSKA.
